PLOW DISK GRINDER

Hubert A. Moore, Dallas, Tex.

Application June 6, 1944, Serial No. 538,908

10 Claims. (Cl. 51—106)

This invention relates to power operated disk grinders for grinding plow disks, cultivator disks or similar circular articles.

One of the objects of the invention resides in the provision of a grinding machine in which the disk to be ground is mounted on a pendulum support with means for the adjustment of the support whereby the disk may be presented to the grinding wheel at the proper angle.

Another object of the invention is to provide in a disk grinding machine, means for grinding a disk in cases where the outside circular disk edge either is or is not concentric with the center hole.

A further object of the invention is to provide in a machine of this type, a single source of power for rotating both the grinding wheel and the disk, and having novel means for adjustment of the disk support toward and away from the grinding wheel without affecting the rotary disk drive.

Other objects will appear hereinafter.

In the accompanying drawings:

Figure 1 is a side elevational view of a grinding machine.

Figure 2 is an end elevation of the same.

Figure 3 is a top plan view of the same, and

Figure 4 is a view, partly in section, taken on the lines A—A of Figure 3.

As illustrated in the accompanying drawings the grinder consists of a framework 1 having legs 2 and provided with a lower platform 3 and an upper platform 4.

Supported on a pair of side members forming part of the lower platform is a support 6 for an electric motor 7 having a drive pulley 8.

The drive pulley drives the grinding wheel belt 9 and the pulley 16 mounted on grinding wheel shaft 11 that is mounted on the upper platform 4. Adjacent opposite ends of the shaft are grinding wheels 12 and 13. The shaft 11 is mounted in fixed bearings 14, bolted at 15 to the longitudinal stringers 5 of the upper platform.

Mounted adjacent the shaft 11 is a second pulley 16 which forms a driving pulley for the horizontally arranged belt 11. The opposite end of the belt 17 is trained over an idle pulley 18 which is mounted on a shaft 19 in bearing support 20. The parts 18 to 20 inclusive are all mounted adjacent the end of one arm of a bell crank lever 21 which is pivoted at 22 to one of the upper side members or stringers 5. The bell crank lever is urged in a clockwise direction about its pivot 22 by a spring 23 which is ad-

justably mounted at 24 to one of the legs 2. The numeral 25 represents an oil cup also mounted on the bell crank lever 21 for lubricating the bearing support 20.

The upper stringers 5 form a support for a pair of brackets. Each bracket is individually adjustable lengthwise of the stringers 5. The bracket 26 is held in adjusted position by the headed screw 28 bearing against the under side of one of the stringers 5, and the bracket 27 is adjustably positioned on its stringer 5 lengthwise thereof by the headed screw 29. Each of the screws 28 and 29 is threadedly engaged through apertures in the lower flanges of brackets 26 and 27 respectively as is diagrammatically shown in Figures 1 and 4. Mounted on the brackets 26 and 27 are pendulum bearings 30 and 31 respectively. These bearings support the pendulum shaft 32. The pendulum 33 consists of a framework having a block support 34 and a bearing block 35. This bearing block supports the shaft 36 on which are mounted stepped pulleys 37. Rotatably mounted adjacent one end of the pendulum shaft 32 is a pulley 38 which pulley is rigid with an axially aligned pulley 39 which latter pulley is driven by the belt 17. The pendulum is rigidly mounted on the sleeve 45, and in this sleeve is rotatably mounted the shaft 32, upon which are rigidly mounted the pulleys 38 and 39. By means of the belt 40 the pulley 38 drives pulley 37 and its shaft 36. Suitable gears, not shown, such as bevelled gears, are respectively attached to one end of the shaft 36 and the lower end of shaft 41. The shaft 41 is mounted in a suitable housing 42 suitably supported by and rigid with the pendulum 33, the upper end of the shaft 41 being provided with a work supporting spool 43. The upper end of this spool may be slightly dished or the same may be flat so as to support the plow disk A. Plow disk A is rigidly held in position on the support 43 by suitable means such as a threaded bolt which projects through the central aperture of the plow disk, not shown, and a nut 44 which readily engages the bolt and may be tightened thereon by the tool 45. The pendulum is provided with a sleeve 46 which is freely rotatable upon the inner shaft 32.

Mounted on the upper flat portion of the bracket 27 is a bolt 47 having an eye 48 at its upper end for the reception of a horizontally arranged bolt 49 whose left end 50, as shown in Figures 3 and 4, is pivotally attached to a crank arm 51 whose lower end is rigidly attached to the pendulum shaft sleeve 32. Mounted on the bolt 49 is a spring 52, one of whose ends is en-

gaged by the threaded nut 53 and whose opposite end bears on the bolt 47. Numeral 54 is a second nut which threadedly engages the bolt 49. The arrangement of the parts is such that the spring 52 continuously urges the horizontally arranged bolt 49 in a leftward direction which latter action causes counterclockwise rotation of the crank arm 51 and sleeve 32.

Inasmuch as the plow disk A is mounted on the pendulum 33 both it and the pendulum tend to be forced to the left or in a counterclockwise direction about the pivot of pendulum shaft 32. The pendulum may be adjusted by loosening the headed screws 28 and 29 and sliding the entire pendulum along the stringers 5 in either direction. It will be noted that the pulley 39 engages the upper and lower reaches of the belt 17 in any position of adjustment of the pendulum longitudinally of the stringers 5.

The parts are driven as follows:

Rotative movement is transmitted from the motor 7 to the grinding wheels 12 and 13 and pulley shaft 11, the rotation of which shaft causes belt 17 to be driven by its drive pulley 16. As stated, in whatever adjusted position the pendulum is in, the upper and lower reaches of the belt cause rotational movement of the pulley 39 which, due to its rigid engagement with the pulley 38, drives this pulley and belt 40 and the shaft 36 through the pulley 37. By means of the gears within bearing block 35 shaft 41 is rotatably driven. Plow disk A is therefore continuously driven by means of the same source of power which drives the grinding wheels.

It will be noted that two grinding wheels are provided. The purpose of the two wheels is to balance each other on the shaft 11. After sufficient wear on wheel 12, which is the grinding wheel mounted to grind the plow disk, this wheel may be taken off and its position exchanged with that of grinding wheel 13. In the ordinary use of the wheel 13, it may be used for general utility purposes.

The shaft 41 is provided with a shaft coupling 55 in order that different length shafts may be used to thereby adjust the relative position in a vertical direction of the work supporting spool 43.

The construction of the pendulum 33 is such that it is substantially balanced about the pivot point 32. However the greater portion of the weight is below the pivot 32. It will be understood that by the present means it is possible to grind a disk which is not concentric with the center hole of the disk, thus saving disk stock.

It will be further understood that the pendulum construction permits grinding at any angle, i. e. the disk may be presented at a plurality of angles to the grinding wheel 12 by adjustment of the pendulum by means of the sliding brackets 26 and 27 toward or away from the said wheel. After the proper adjustment has been made the knurled screws are tightened and the pendulum may be manually swung around the pivot 32 or adjustment may be made of the threaded nuts 53 and 54 to cause the work to be forced by the spring 52 in the direction of the rotating grinding wheel, and held against the wheel during the grinding operation.

It is to be understood that the form of the invention shown and described is to be taken as a preferred example of the same and that various changes of the shape, size and arrangement of parts and accessories may be resorted to without departing from the spirit of the invention or the scope of the claims.

I claim:

1. In a disk grinder, a framework, a grinding wheel mounted thereon, means for rotating said grinding wheel, a pendulum having a lower freely swingable end, means for pivotally mounting said pendulum on said framework, a disk holder mounted on said pendulum, means for adjustably securing said pendulum different distances from said grinding wheel, and means driven from said grinding wheel for rotating said disk holder, said last-named means including a belt driven by said grinding wheel, and a driven pulley on said pendulum in driving relation with said belt, said driven pulley being mounted on said means for pivotally mounting said pendulum, said pendulum extending beneath said last named means.

2. In a disk grinder, a framework, stringers forming part of said framework, a grinding wheel mounted on said framework, means for rotating said grinding wheel, a pendulum having a lower freely swingable end, means for pivotally mounting said pendulum on said framework, a disk holder mounted on said pendulum, means for securing said pendulum on said stringers different distances from said grinding wheel, and means driven from said grinding wheel for rotating said disk holder, said last-named means including a horizontally arranged belt, a pulley on said grinding wheel and a second pulley on said pendulum adapted to be engaged by and driven from said belt, said belt having substantially parallel runs adapted to move in opposite directions, said pendulum pulley being mounted to be drivingly engaged by said parallel belt runs at different distances along the belt runs from said grinding wheel, in accordance with adjustments made by said pendulum securing means.

3. In a disk grinder, a framework, stringers forming part of said framework, a grinding wheel mounted on said framework, means for rotating said grinding wheel, a pendulum having a lower freely swingable end, means for pivotally mounting said pendulum on said framework, a disk holder mounted on said pendulum, means for securing said pendulum on said stringers different distances from said grinding wheel, and means driven from said grinding wheel for rotating said disk holder, said last-named means including a pulley driven by said grinding wheel, a second pulley on said pendulum, and a belt connecting said pulleys, said pendulum pulley being located intermediate the length of said belt, and adapted to engage said belt at different distances along the belt runs from said grinding wheel as said pendulum is adjustably secured at different distances from said grinding wheel.

4. In a disk grinder, a framework, stringers on said framework, a grinding wheel mounted thereon, means for rotating said grinding wheel, a pendulum having a lower freely swingable end, means for pivotally mounting said pendulum on said framework, a disk holder mounted on said pendulum, means for securing said pendulum on said stringers different distances from said grinding wheel, and means driven from said grinding wheel for rotating said disk holder, said last-named means including a horizontally arranged belt, a pulley on said grinding wheel, a second pulley on said pendulum adapted to be engaged by and driven from said belt, and a third pulley located adjacent the bottom of said pendulum and a shaft driven by said last-named pulley, said shaft being connected to said disk holder.

5. In a disk grinder, a framework, stringers forming part of said framework, a grinding wheel

mounted on said framework, means for rotating said grinding wheel, a pendulum, having a lower freely swingable end, means for pivotally mounting said pendulum on said framework, a disk holder mounted on said pendulum, means for securing said pendulum on said stringers different distances from said grinding wheel, means driven from said grinding wheel for rotating said disk holder, said last-named means including a horizontally arranged belt, a pulley on said grinding wheel, a second pulley on said pendulum adapted to be engaged by and driven from said belt, and a third pulley located adjacent the bottom of said pendulum and a shaft driven by said last-named pulley, said shaft being connected to said disk holder, and means on said pendulum for resiliently pressing the disk holder by said disk holder against said grinding wheel.

6. In a disk grinder, a framework, said framework having a horizontal surface, a grinding wheel mounted on said framework, means for rotating said grinding wheel, a pendulum having a lower freely swingable end, means for pivotally mounting said pendulum on the horizontal surface of said framework, a disk holder mounted on said pendulum, means for adjustably securing said pendulum on the horizontal surface of said framework different distances from said grinding wheel, means driven from said grinding wheel for rotating said disk holder, said last-named means including a pulley on said grinding wheel, a plurality of pulleys on said pendulum a belt for drivingly connecting said grinding wheel pulley and one of said pendulum pulleys, one of said pulleys being driven by said belt, a second belt, said second belt being drivingly connected to others of said pulleys a shaft on said pendulum, and means attaching said disk holder to said shaft.

7. In a disk grinder, a framework, a grinding wheel mounted thereon, a pendulum having a freely swingable end, means for pivotally mounting said pendulum on said framework, a disk holder mounted on said pendulum, means for adjustably securing said pendulum different distances from said grinding wheel, means for drivingly connecting said grinding wheel and said disk holder including an endless flexible drive means, a driven means on said pendulum and directly connected by said flexible drive means to said grinding wheel in driving engagement with said grinding wheel, and a driving connection means from said driven means extending to said pendulum end and from the same to said disk holder.

8. In a disk grinder, a framework, a grinding

wheel mounted thereon, means for rotating said grinding wheel, a pendulum having a lower freely swingable end, means for pivotally mounting said pendulum on said framework, a disk holder mounted on said pendulum, means for adjustably securing said pendulum different distances from said grinding wheel, and means for rotating said disk holder including a belt having substantially parallel runs, pulleys at opposite ends of said belt, means for driving said belt from one of said pulleys, and a third pulley located intermediate said first-named pulleys and being mounted to simultaneously engage the substantially parallel surfaces of said belt and being driven thereby, and a shaft driven by said intermediate pulley in driving relation with said disk holder.

9. In a disk grinder, a framework, a grinding wheel mounted thereon, means for rotating said grinding wheel, a pendulum having a lower freely swingable end, means for pivotally mounting said pendulum on said framework, a disk holder mounted on said pendulum, means for adjustably securing said pendulum different distances from said grinding wheel, and means for rotating said disk holder including a belt having substantially parallel runs, pulleys at opposite ends of said belt, means for driving said belt from one of said pulleys, and a third pulley located intermediate said first-named pulleys and being mounted to simultaneously engage the substantially parallel surfaces of said belt and being driven thereby, a shaft driven by said intermediate pulley in driving relation with said disk holder, and means mounting the other of said opposite end pulleys including means for maintaining said belt under tension.

10. In a disk grinder, a framework, a grinding wheel mounted thereon, means for rotating said grinding wheel, a pendulum having a lower freely swingable end, means for pivotally mounting said pendulum on said framework, a disk holder mounted on said pendulum, means for adjustably securing said pendulum different distances from said grinding wheel, and means for rotating said disk holder including a belt having substantially parallel runs, pulleys at opposite ends of said belt, means for driving said belt from one of said pulleys, and a third pulley located intermediate said first-named pulleys and being mounted to simultaneously engage the substantially parallel surfaces of said belt and being driven thereby, a shaft driven by said intermediate pulley in driving relation with said disk holder, and adjustable means for maintaining said belt under tension.
